UNITED STATES PATENT OFFICE

147,637

DESIGN FOR A MILK TRUCK

Charles I. Brockriede, Columbiaville, Mich.

Application February 18, 1946, Serial No. 126,679

Term of patent 3½ years

(Cl. D14—3)

To all whom it may concern:

Be it known that I, Charles I. Brockriede, a citizen of the United States of America, residing at Columbiaville, in the county of Lapeer and State of Michigan, have invented a new, original, and ornamental Design for a Milk Truck, of which the following is a specification, reference being had to the accompanying drawing, forming a part thereof.

In the drawing:

Figure 1 is a top plan view of a milk truck showing my new design.

Figure 2 is a side elevational view of the same.

Figure 3 is a front elevational view of the same.

I claim:

The ornamental design for a milk truck as shown.

CHARLES I. BROCKRIEDE.
